FLOOR PROTECTING PLATE

Vinton E. Sisson, Winnetka, Ill., assignor, by
mesme assignments, to Standard Railway
Equipment Manufacturing Company, a corpora-
tion of Delaware

Application August 7, 1936, Serial No. 94,806

6 Claims. (Cl. 105—422)

The invention relates to railway freight cars preferably of the house or roofed type and has for its object to provide means for protecting the wooden floors now in general use in such type of equipment, which means will not interfere with the securing of blocking to the wooden flooring, to which the lading is secured.

Another object of the invention is to provide a metallic protecting sheathing which rests upon the wooden flooring of the railway car and is provided with apertures or perforations so that the car lading may be nailed or otherwise secured to the flooring through the apertures.

Another object is to shape the apertures so that they are long enough to provide a relatively large area for nailing and are relatively narrow so that the wheels of loading trucks or shoes of workmen will not get caught therein.

Another object is to form the sides of the elongated apertures with stiffening flanges to prevent the edges of the apertures from curling up and also to stiffen the sheathing as a whole against buckling. These stiffening flanges may project downwardly and be imbedded in the wooden flooring to help hold the sheathing in place or they may project upwardly so as to provide means to prevent slipping. I prefer to project some flanges upwardly and some downwardly.

The apertures are preferably positioned in a staggered relationship with the end portions thereof overlapping each other so that the several flanges of the several apertures cooperate to reinforce and stiffen the sheathing.

Another object is to shape the elongated apertures with non-parallel sides to provide relatively narrow end portions and a relatively wide middle portion so that the edge of the plate around the apertures will have a tendency to lie flat instead of bending up.

Another object of the invention is to provide a metallic sheathing wherein some of the elongated apertures are positioned with their long dimension parallel to the short dimension of some of the other apertures and to provide said elongated apertures with flanges along their sides which are substantially parallel with each other for use in driving the flanges into the wooden floor.

In the drawings:

Fig. 1 shows a floor plan of part of a railway box car equipped with my floor protection.

Fig. 2 is a section on line 2—2 of Fig. 1.

Fig. 3 is a section on line 3—3 of Fig. 1.

Figs. 4 to 11 inclusive show various forms of apertures in the metallic sheathing.

In the form of my invention illustrated, the usual parts of the car are shown, such as the center sills 2, side sill 3, door posts 4 and wooden flooring 5. The wooden floor 5 usually comprises a plurality of wooden shiplapped or tongued and grooved boards extending laterally of the car which are secured directly or indirectly to the center sills 2, side sill 3 and floor stringers (if used).

My metallic sheathing 1 rests on the top of the wooden floor 5 and is preferably secured thereto by bolts, screws or nails.

I preferably provide an elongated substantially diamond shaped aperture 10—11—12—13—14 wherein the middle thereof is relatively wide 15 with end portions tapering to points or rounded terminals. By this arrangement a very large area of opening is provided for nailing but at the same time only a relatively small thing may penetrate the aperture. This shape of aperture 20 presents substantially convex sides which do not have a tendency to kick up.

The sides of the aperture, or parts thereof, are provided with stiffening flanges which may project upwardly to provide anti-slipping means or 25 may project downwardly and be imbedded in the wooden floor to hold the sheathing down and from moving parallel to the top of the wooden floor. These flanges are preferably positioned parallel to the grain of the wood so that they 30 may be easily driven into the wooden flooring.

The flanges of some of the apertures may project upwardly and the flanges of other apertures may project downwardly for the purposes specified, and in fact, the flanges of a single aperture 35 may project upwardly and downwardly and come within the scope of the invention.

Figs. 4 and 5 show my preferred form of aperture, wherein Fig. 5 is a section on line 5—5 of Fig. 4. The elongated aperture 10 has a relatively wide middle part with parallel sides 15 with the sides 16 of the end portions merging into pointed ends 18. The parallel side portions 15 are provided with pointed or rounded flanges 20.

Figs. 6 and 7 show a modified form of aperture (11) wherein Fig. 7 is a section on line 7—7 of Fig. 6. The sides of the aperture are provided with flanges 22 following the contour of the side edges of the aperture and merging (24) 50 into the sheathing adjacent the opposite ends 26 of the aperture. This aperture is formed by slitting the plate along line 7—7 from 30 to 32 and forming the flanges of the material between the sides of the aperture and this slit. 55

Figs. 7 and 8 show a modification wherein Fig. 9 is a section on line 9—9 of Fig. 8. This elongated aperture 12 is curved with the convex edge 34 thereof formed with a flange 36 extending substantially to the ends of the aperture.

The apertures may be arranged in parallel rows with the ends of apertures in adjacent rows overlapping or positioned in staggered relationship, as shown to the right in Fig. 1, or the apertures 10 may be positioned in parallel rows with adjacent apertures positioned normal to each other for overlapping relationship, as shown to the left in Fig. 1.

Figs. 10 and 11 show a modification wherein Fig. 11 is a section on line 11—11 of Fig. 10. The preferably elongated apertures are substantially rectangular in shape and are positioned with the longitudinal axes of one group thereof substantially normal to the axes of another group there 20 of, as shown on the left side of Fig. 1. The apertures 13 of one of these groups are provided with flanges 40 at the long sides of the rectangle and the apertures 14 of the other group are provided with flanges 41 at the short sides of the 25 rectangle so that the flanges 40—41 of all of the apertures are substantially parallel with each other. The metallic sheathing 7 is preferably laid upon the wooden floor 5 with the flanges extending substantially parallel with the grain of 30 the wood so that they may be easily driven into the wood.

In Figs. 9 and 10, I have shown saw tooth flanges 40 which when projecting upwardly form an efficient non-skid construction and when projecting downwardly can be easily driven into the 35 wood.

The accompanying drawings illustrate the preferred form of the invention, though it is to be understood that the invention is not limited to 40 the exact details of construction shown and described, as it is obvious that various modifications thereof, within the scope of the claims, will occur to persons skilled in the art.

I claim:

45 1. In a railway car having a wooden floor and a metallic sheathing resting upon the floor and provided with a plurality of elongated apertures so that car lading may be secured to the wooden floor through the apertures, the sides of some apertures formed with depending stiffening flanges and the sides of other apertures formed with up- 50 standing stiffening flanges, said flanges merging

into the sheathing adjacent the ends of the apertures.

2. In a railway car having a wooden floor and a metallic sheathing, a plurality of apertures so that car lading may be secured to the wooden floor through the apertures, each aperture having parallel sides and tapered ends, the parallel side portions of the apertures formed with depending stiffening flanges.

3. In a railway car having a wooden floor and a metallic sheathing resting upon the floor and provided with a plurality of diamond shaped apertures so that car lading may be secured to the wooden floor through the apertures, the sides of said apertures formed with depending stiffening flanges which merge into the sheathing adjacent the ends of the apertures.

4. In a railway car having a wooden floor and a metallic sheathing resting upon the floor and provided with a plurality of elongated apertures so that car lading may be secured to the wooden floor through the apertures, said apertures positioned in staggered relationship with the end portions thereof overlapping each other, the sides of some apertures formed with depending stiffening flanges.

5. In a railway car having a wooden floor and a metallic sheathing resting upon the floor and provided with a plurality of elongated apertures so that car lading may be secured to the wooden floor through the apertures, said apertures positioned with the long axes of one group substantially normal to the long axes of another group, said apertures provided with flanges on the long sides of one of said groups and on the short sides of the other of said groups so that the flanges are substantially parallel, said sheathing laid upon said wooden floor with the said flanges substantially parallel with the grain of the wood for the purpose specified.

40 6. In a railway car having a wooden floor and a metallic sheathing resting upon the floor and provided with a plurality of substantially rectangular apertures so that car lading may be secured to the wooden floor through the apertures, said apertures provided with flanges on the opposite sides only thereof which are positioned so that the flanges are substantially parallel, said sheathing laid upon said wooden floor with the said flanges substantially parallel with the grain of the wood for the purpose specified.

VINTON E. SISSON.
